UNITED STATES PATENT OFFICE.

MARIE YVES DELAGE, OF PARIS, FRANCE.

MAGNETO-CONTROLLING DEVICE.

1,315,911.

Specification of Letters Patent. Patented Sept. 9, 1919.

Application filed June 29, 1917. Serial No. 177,675.

To all whom it may concern:

Be it known that I, MARIE YVES DELAGE, residing at Paris, France, have invented a new and useful Magneto-Controlling Device, 5 of which the following is a specification.

This invention relates to a device for controlling a magneto for producing a magneto spark on semi-heavy motors and the like so that they can be started up by hand.

10 Explosion motors of the slow and semi-slow, and consequently semi-heavy, type, as used for navigating and certain other purposes, require either a battery or an accumulator, and a self-induction coil for starting them up. It has not been possible, as a matter of fact, to start this type of motor by hand with a magneto, in that it is impossible to impart sufficient speed to the flywheel to obtain sparks from a rotary magneto. Batteries and accumulators are a source of trouble and necessitate a considerable expense for upkeep.

15 The object of the present invention is to enable these heavy motors to be started by hand without deriving ignition sparks from any other source than their magneto.

The principle of the apparatus is as follows, namely, that by utilizing the cam shaft, and a second and larger multiplication driving gear added to the direct drive of the magneto, this multiplication driving gear may be thrown into engagement only for starting up the motor, and may be automatically thrown out of gear after a certain 20 number of revolutions which are found in practice to be sufficient to start it. A permanent increase of the multiplication gear would be attended by the threefold drawbacks of a useless expenditure of power, 25 rapid wear and tear of the gearing, and deterioration of the windings.

The apparatus may be constructed as hereinafter described.

Figure 1 shows the apparatus in side elevation parallel to the cam shaft; and

Fig. 2 is an end view from the left-hand side of Fig. 1, (the lower part of the frame carrying the complete gear being shown removed in order to avoid concealment of the 50 gearing).

The driving pinion 1 of the magneto is constructed loose upon the cam shaft 2, to which it is connected by a ratchet 3 and a

pawl 4, the latter controlled by a spring 5 so as to be actuated by the cam shaft 2 when 55 no other extraneous force causes it to rotate more quickly than the said cam shaft in the same direction. To this pinion 1 there is fastened another pinion 6 cast in one piece with the pinion 1, but of smaller diameter, 60 and also loose on the shaft 2. A short distance away there is fastened to the shaft 2 a spur wheel 7, which, as in the case of the pinion 1, is mounted loosely upon the shaft 2; this wheel 7 is connected to the shaft by a 65 ratchet 8 and a spring-controlled pawl 9 with its spring 9¹ operated in the same direction as the pinion 1.

Parallel to the shaft 2 is arranged a spindle 10 to which there are keyed the pinion 12 70 engaging with the spur wheel 7 and also a spur wheel 11 of larger diameter, which engages with the pinion 6.

The effect of this arrangement is that, 75 when the shaft 2 rotates in a normal direction, it rotates also the pinions 1, 6 and 7. The pinion 7, by reason of its respective diameters, communicates an increased speed to the pinion 12 which, through the medium of the shaft 10, rotates the pinion 11 at the 80 same angular velocity, but this latter, being in gear with the pinion 6, causes rotation of the latter and of the bevel pinion 1 at an accelerated velocity in accordance with their 85 different diameters. The effect of this is 90 that the pinions 1 and 6 rotate more quickly than the shaft 2, this increase of velocity being rendered possible by reason of the ratchet and pawl 3, 4. The pinion 1 thus rotates at this increased velocity the pinion 13 fixed to the spindle 14 of the winding of the magneto 15. (In the drawings, the parts 14, 15 of the magneto have been rotated through a right angle toward the bottom of the figure, in order not to confuse 95 the drawing). This is the arrangement which is brought into play when the motor is started up by hand at a very low speed.

The increase of speed brought about by the multiplying gear must be at a given ratio 100 in accordance with the number of cylinders. It is necessary that other conditions should be observed; firstly, that the multiplication should be fairly large so as to cause sparking from the magneto at the speed which is 105 imparted to it when operating the flywheel

by hand; secondly, it is necessary that the multiplication should be such as is not likely to get the magneto out of time, this condition being realized when the multiplication 5 is equal to a whole number.

In practice, all the cylinders must ignite at each revolution of the cam shaft. Hence, an ignition must take place therein for each fraction of the revolution of the cam shaft 10 equal to $\frac{1}{Q}$. Q being the number of cylinders; directly, therefore, an ignition takes place, a second ignition should be produced when the cam shaft is rotated to the extent 15 of $\frac{1}{Q}$. Now, when 2 is rotated to the extent of $\frac{1}{Q}$. 1 will have rotated to the extent of $\frac{M}{Q}$. (M being the total multiplication of the 20 multiplying gear equal to the product of the two intermediate multiplications) and, in order that 1 may be in the right position at this moment, it is necessary that it should be turned by one whole 25 number of revolutions per $\frac{1}{Q}$. It is, therefore, necessary that $\frac{M}{Q}$ should be an exact

30 multiple of $\frac{1}{Q}$, that is to say, M must be a whole number. However, the magneto being bi-polar, if for a rotation of 1 equal to $\frac{1}{Q}$ it 35 makes more than the minimum equal to one-half rotation, if for example, it makes V semi-rotations, then it will furnish sparks at each semi-rotation, that is to say, V times, 40 while 1 will turn $\frac{1}{Q}$. In this case, therefore, it will be in a position to furnish sparks every time it has turned to the extent of $\frac{1}{QV}$.

45 instead of every time 1 is turned by $\frac{1}{Q}$, and the condition will then be that M is an exact multiple of $\frac{1}{V}$. If 7 were always fixed on 2, 50 it might happen, if by mischance the motor were started a little in advance of the ignition, that the piston would be forced in a direction contrary to the normal travel. The result would be that 1 would endeavor to 55 rotate more quickly than 2 in the direction opposed by its ratchet and pawl, and the apparatus would be broken. Thanks, however, to the ratchet 8 and pawl 9 of the pinion 7, the shaft 2 does not engage the pinion 60 7 when it rotates in a direction opposed to the normal, and this drawback is thus avoided. Matters being thus arranged, the motor may be run by starting with the hand, but the speed of rotation of the magneto

would be much too high if the motor were 65 to rotate at its usual speed, and the drawbacks mentioned above would ensue. It is therefore necessary to supplement the apparatus by an arrangement causing the automatic disengagement of the multiplication 70 gear after a small number of revolutions sufficient to start up the motor.

Such an arrangement may be as follows:

The counter-shaft 10 is arranged to slide longitudinally in its bearings 16 and 17 75 through which it projects at either end. At the end 16 a ring 18 on the shaft 10 limits its lateral movement toward the right. At the end 17, the shaft 10 is screw-threaded for a certain portion of its length, and this 80 screw-threaded portion is limited by the two shoulder pieces 19 and 20. Upon this threaded portion is screwed a short sleeve 21, which is shorter than the space between the shoulder pieces 19 and 20 so that the sleeve 85 can move somewhat upon 10 in one direction or the other, according as it is screwed up or unscrewed, its movement being restricted by the shoulder-pieces 19 and 20. At its outer end the sleeve 21 is fitted with lugs which 90 enable it to be screwed up or unscrewed by hand. The sleeve 21 is also provided over part of its length with an external thread consisting of a few threads only of the same pitch as its internal threads. For the remainder of its length, the sleeve 21 is smooth and reduced in diameter where it occupies the bearing 17.

The bearing 17 is itself screw-threaded internally over a portion of its length, the 100 pitch and diameter of the thread being the counter-part of the thread on 21, so that, upon rotation of 21 upon the shaft 10, it is at the same time screwed into or out of the journal 17. Finally, a coiled spring 22 is 105 mounted on 10 between the boss of the pinion 11 and the adjacent journal 16, and tends to press the shaft 10 toward its screw-threaded end until stopped by the ring 18.

In the position shown in the drawing, the 110 multiplication gear is shown in engagement; in this position, the part 21 is screwed into the journal 17 and bears against the collar 19; and there remains on 10 between the end of the sleeve 21 and the collar 20 as many 115 free threads as there are threads of 21 screwed into the bearing 17. The number of revolutions, therefore, which the apparatus must take prior to becoming disengaged, is determined precisely by the position of the collars 19 and 20 upon the shaft 10. In the position of engagement of the multiplying gear, if the flywheel be turned by hand, the shaft 10 on its rotation will be locked to the sleeve 21 owing to the collar 19 120 being screwed against the end of 21. The shaft 10, therefore, also unscrews the sleeve 21 from its bearing 17. After a few revolu-

tions, during which the ignition of the motor takes place owing to the multiplication gear speeding up the magneto, the sleeve 21 is disengaged and the spring 22 then pushes the 5 shaft 10 toward the right until stopped by the collar 18, but far enough to throw the multiplying wheels out of gear, at which moment the driving of the magneto is effected direct on the normal speed increase 10 given by the pinions 1 and 13.

After stoppage of the motor, and in order to start it afresh, the following steps are taken:

Unscrew the sleeve 21 on the shaft 10 by 15 means of its lugs until it bears against the collar 20; then push the part 21 against the compression of the spring 22 so as to engage the pinions, at the same time screwing 21 into the bearing 17 and along the shaft 10 20 until it reaches the collar 19. The apparatus is then ready to restart.

It should be noticed that the number of threads of 21 engaged in the bearing 17 must be such as will allow of the cam shaft making 25 at least one revolution prior to the sleeve being thrown out of engagement, so that the sleeve 21 must screw itself by at least as many turns as there are units in the multiplication of the pinions 7 and 12.

30 Finally, when the multiplying apparatus is thrown out of gear, it leaves the pinion 1 in any position due to the speed required, so that, if the shaft 2 immediately rotated 1, then the magneto would be very likely 35 to be thrown out of time.

This drawback has been overcome by the following structural arrangement:

If 1 were fixed on 2, the magneto, when once adjusted, would not be disarranged by 40 the fact of rotation, the relative positions of 1 and 2 being unchangeable. In the present invention, however, 1 is loose on 2, and 2 rotates 1 in the normal direction of rotation only by means of the ratchet 3 keyed to 45 2 and of the spring pawl 4 affixed to 1. If the ratchet 3 had only one tooth, and if the adjustment of the magneto were realized when the tooth of the ratchet engages the pawl, then the adjustment might be moment- 50 tarily destroyed, but would be automatically reestablished. It would, as a matter of fact, be destroyed because 2 would have engaged in advance with 1; directly the multiplying apparatus ceased to act (2 continuing to 55 rotate while 1 no longer rotated) the ratchet would reengage the pawl and the adjustment of the magneto would be reestablished. It will be apparent, however, that in this case, 1 may be able to accomplish almost an en- 60 tire revolution before the adjustment is re-established. It is, therefore, preferable to make the ratchet with the maximum number of teeth compatible with retaining the adjustment. This maximum number is

double the multiplication imparted by the 65 pinions 1 and 13; if, for instance, this multiplication be 3, then the maximum number of the ratchet teeth would be 2×3 equals 6. As a matter of fact, if we call T the multiplication due to pinions 1 and 13, then, 70 if 1 makes one revolution, 13 will make T revolutions. The magneto, being bi-polar, passes twice at each revolution into position for adjustment. It, therefore, passes into this position 2T, times to each revolution of 1. On 1 there are thus 2T equidistant points which can be indifferently substituted one for the other without alteration of the adjustment of the magneto. Hence if 2T teeth be given to the ratchet, 80 the magneto will remain adjusted or regulated quite irrespective of which one of these teeth will engage the pawl. On the contrary, any other point of engagement and, consequently, any tooth in excess of 2T 85 would cause the magneto to be thrown out of time, if by chance the engagement were effected by its intervention.

The whole of the multiplying apparatus may be mounted in a three-sided frame 23 90 supporting the shaft 10 and the ends of which, on the open side, are provided with bearings 24 and 25 traversed by the cam shaft 2, so that the frame is supported by this shaft. It then suffices to simply affix 95 this frame to the framework of the machine at such a point as 26 in order to prevent the whole from turning. If the bearings 24 and 25 carrying the frame are in two pieces, then the multiplying apparatus may be 100 added with the greatest ease to any type of existing motor, without modifying its construction and without much trouble, thanks to modifications which are simple and of 105 moderate cost.

Having now particularly described and ascertained the nature of my said invention, and in what manner the same is to be performed, I declare that what I claim is:

1. A magneto accelerating device including an upper and lower shaft, a large and small gear mounted on each of said shafts adapted during starting to register with the opposite small and large gear respectively, the smaller gear upon the lower shaft being loosely mounted thereon and carrying means adapted to drive a magneto, and means associated with the upper shaft for moving the same longitudinally whereby to disengage the gears thereon from the gears 110 upon the lower shaft after a certain number of revolutions.

2. A magneto accelerating device including an upper and lower shaft, a large and small gear mounted on each of said shafts 115 adapted during starting to register with the opposite small and large gear respectively, the smaller gear upon the lower shaft be-

ing loosely mounted thereon and carrying means adapted to drive the magneto, means associated with the upper shaft for moving the same longitudinally whereby to disengage the gears thereon with the gears upon the lower shaft after a certain number of revolutions, and further means for locking said loose gear to the lower shaft after the

gears on the upper shaft have been thrown out of engagement therewith.

In testimony whereof I affix my signature in presence of two witnesses.

MARIE YVES DELAGE.
